UNITED STATES PATENT OFFICE.

GEORGE A. KOHOUT, OF CHICAGO, ILLINOIS, ASSIGNOR TO KERSTO CORPORATION, OF CHICAGO, ILLINOIS.

AUTOMATIC FURNACE-STOKER.

1,243,186.

Specification of Letters Patent. Patented Oct. 16, 1917.

Application filed February 25, 1916. Serial No. 80,358.

To all whom it may concern:

Be it known that I, GEORGE A. KOHOUT, a citizen of the United States, residing at Chicago, in the county of Cook and State 5 of Illinois, have invented a certain new and useful Improvement in Automatic Furnace-Stokers, of which the following is a full, clear, concise, and exact description, reference being had to the accompanying drawings, forming a part of this specification.

My invention relates to automatic furnace stokers and has for its object the provision of an improved device of this nature which is simple in construction and efficient in its 15 operation.

My invention contemplates improved means for controlling the starting and stopping of the automatic stoker including safety appliances for protecting the stoker in the 20 event of accident. My invention contemplates the use of a deflector plate which directs the fuel discharged into the furnace to its proper place, this deflector being preferably hollow so that it may be air or steam 25 cooled, which air or steam may be used at the same time to assist in cleaning the face of the deflector after each charge, or may be used to assist in throwing the fuel into position. My invention further contemplates 30 means whereby the air or steam supply may be intermittent so intermittent steam jets along the face of the deflector may be caused synchronously with each operation of the fuel throwing device.

I will explain one form which my invention may take illustrating the above features and others which will be apparent more in detail by referring to the accompanying drawings, in which—

Figure 1 is a longitudinal sectional view of my improved stoker as applied to a furnace;

Fig. 2 is a front view of the stoker;

Fig. 3 is a side view of the stoker;

Fig. 4 is a sectional view on line *b*—*b* of Fig. 5;

Fig. 5 is a sectional view on line *c*—*c* of Fig. 2;

Fig. 6 is a front view of the deflector;

Fig. 7 is a top view of the deflector;

Fig. 8 is a view of a modified form of deflector, and

Fig. 9 is a detail of construction.

Referring more particularly to Fig. 1, I 55 show a furnace 1 having the grate bars 2,

the cleaning doors 3, and the firing doors 4, these firing doors 4 also being more clearly shown in Fig. 4 where they are shown as cut away to accommodate my improved automatic stoker appliance. My improved automatic stoker is shown as applied to the front of the furnace and projects into the furnace through the cut away portions of the firing doors 4. My improved stoker consists of the structure comprising the base plate 5 to 60 which are attached the forwardly extending webs or ribs 6, which ribs form a compartment to protect certain gearing as will be apparent hereinafter. The base plate structure is also integral with a measuring chamber 7 and carries bearings 8 and 9 adapted to accommodate a shaft 10, which shaft carries the measuring device 11. This measuring device 11 has pockets 12 and 13 which are of unequal size so that different quantities of fuel are alternately deposited for discharge into the furnace, thus to secure even distribution throughout the entire grate surface. The integral structure including the parts 5, 6, 8, 9 and 11 also consists of a forwardly extending tubular structure 14 within which a piston 15 is mounted, which piston throws the fuel deposited in front of it into the combustion chamber. The shaft 10 carries a bevel gear 17 which is driven by a 65 companion bevel gear 18 mounted upon the main drive shaft 19. Upwardly of this integral structure are mounted two cup-shaped elements 20 and 21 which are bolted together 70 and secured on the top of this structure, thereby to form a pocket or chamber 22 within which crushers 23 and 24 operate to crush the fuel deposited into the hopper 25 before it reaches the pockets 12 and 13. These crushers are mounted on shafts 26 and 27 respectively and the shaft 27 is provided with a sprocket wheel 28 driven by means of the chain 29 from a sprocket wheel 30 carried by the main drive shaft 19. The shaft 27 also carries a gear wheel 31 which meshes 75 with a second gear wheel 32 provided upon the shaft 26. Thus the crushers are driven directly from the main power shaft 19 as readily apparent. The elements 20 and 21 are of course suitably bolted to the base 80 plate by means of the bolts 33, and the hopper 25 is suitably attached in any desirable manner. A door 34 preferably hinged closes the chamber within which the gear wheels 17 and 18 are mounted. The shaft 19 is 85 80 85 90 95 100 105 110

suitably held in bearings 35 as seen most clearly in Fig. 2. This drive shaft 19 is driven from the power shaft 36 through the interposition of clutch elements 37 and 38, the finger 39 of a control lever being indicated to move the clutch element 38 to the right or left, thus to cause the pin 40 to engage the projection 41 to thereby drive the shaft 19. This pin 41 is of such characteristics that it will break and prevent further driving of the shaft 19 should any part of the stoker mechanism become clogged beyond the limits of safety. The power shaft 19 likewise carries a cam 42 which is rotated therewith and which has pins 43 and 44 adapted to engage projections 45 and 46 respectively of a sliding framework 47, which sliding framework has rollers 48 moving in guides 49 provided in the integral base plate structure. This sliding framework consists also of the webs 50 and 51 on opposite sides thereof which carry arms 52 and 53 that engage retractile springs 54 and 55. This sliding framework also has the downwardly extending fingers 56 and 57 extended downwardly from the webs 51 and 52, these fingers carrying percussion plates 58 and 59 faced with leather 60 which are adapted to abut against the recoil springs 61, 62, 63 and 64.

It is to be understood of course that the sliding framework 47 is moved to the left (Fig. 3) by the pins 43 and 44 and when the pin 44 leaves the projection 46 this sliding framework due to the springs 54 and 55 is thrown violently to the right, the springs 61 to 64 inclusive then taking the recoil after the fuel has been discharged from in front of the piston 15 to prevent breakage of the apparatus and to reduce the noise. Two halves of the sliding framework are fastened to a rod 65 which passes through the piston 15, this rod being fastened to the sliding framework elements by the bolts 66 and 67. The piston 15 when it is moved to the left (Fig. 5), of course is moved far enough to the left so that it is at the left of the passage-way 16 to permit fuel from the pockets 12 or 13 to drop into the piston chamber 68 so that the piston upon its recoil may throw the deposited fuel against the deflector 69 where it is deflected and distributed over the grate bars 2.

The outline of the deflector plate will be more clearly apparent from an inspection of Figs. 5, 6 and 7. This deflector has the rounded upper surface 70 and is provided with a hollow interior 71 into which steam may be led by the pipe 72 which receives its steam from the supply pipe 73. The deflector is also provided with nozzles 74, 75 through which steam from the chamber 71 may pass out and flow in a line substantially parallel to the face of the deflector. This steam may be used to clear the deflector

after each discharge, or may be used even at the time that the fuel is being discharged. The steam within the chamber 71 serves to keep the deflector at a reasonable temperature. The supply pipe 73 may receive its steam directly from the main supply pipe 76 through the by-pass 77 provided the valve 78 is open, at which time there is a continuous flow of steam. Should the valve 78 be closed, however, then the steam would have to travel through the pipe 79 which is controlled by a valve 80, this valve 80 being controlled directly by a cam 81, which cam operates in response to the movements of the power shaft 19, as shown in Fig. 9. Preferably the valve 80 is then opened twice for each complete revolution of the operating shaft 19.

In Fig. 8, I show a modified form of structure for the deflector 69 in that in addition to the steam chamber 71 I provide a water cooling chamber 82 to which water may be led to further cool the deflector as may be desired.

From what has been described it is thought the nature of my invention will be readily clear to those skilled in the art. Having however thus described one form which my invention may take, what I claim as new and desire to secure by Letters Patent is:

1. An automatic stoker having a fuel reservoir, a charge receptacle, means for feeding fuel from said reservoir to said charge receptacle, means for discharging said fuel from said charge receptacle, a deflector in the path of the discharged fuel, means for supplying steam associated with said deflector, a drive shaft for controlling said two first aforesaid means, and means conjointly with said drive shaft to control said steam supply.

2. An automatic stoker comprising a centrally located casing, said casing having a feed controlling chamber and a discharge chamber, a measuring device in said feed controlling chamber, a piston in said discharge chamber, a sliding framework exteriorly of said casing associated with said piston, a power shaft to actuate said measuring device and said framework, rollers carried by said framework, guides carried by said casing within which said rollers operate to permit of a reciprocatory movement of said framework, a retractile spring for restoring said framework, and a percussion spring to take the recoil as this framework is being restored to its initial position.

3. An automatic stoker comprising a centrally located casing, said casing having a feed controlling chamber and a discharge chamber, a measuring device in said feed controlling chamber, a piston in said discharge chamber, a sliding framework exteriorly of said casing associated with said

5 piston, a power shaft to actuate said measuring device and said framework, a cam interposed between said power shaft and said framework, rollers carried by said framework, guides carried by said casing within which said rollers operate to permit 10 of a reciprocatory movement of said framework, a retractile spring for restoring said framework, and a percussion spring to take 15 the recoil as this framework is being restored to its initial position.

4. An automatic stoker comprising a centrally located casing, said casing having a feed controlling chamber and a discharge 15 chamber, a measuring device in said feed controlling chamber, a piston in said discharge chamber, a sliding framework exteriorly of said casing associated with said piston, a power shaft to actuate said measuring device and said framework, a pair of pins on said framework, retractile springs 20 associated with said pins, and a recoil spring associated with said framework.

5. An automatic stoker comprising a centrally located casing, said casing having a feed controlling chamber and a discharge chamber, a measuring device in said feed controlling chamber, a piston in said discharge chamber, a sliding framework exteriorly of said casing associated with said piston, a power shaft to actuate said measuring device and said framework, a cam interposed between said power shaft and said framework, a pair of pins on said framework, retractile springs associated with said pins, and a recoil spring associated 35 with said framework.

6. An automatic stoker comprising a centrally located casing, said casing having a feed controlling chamber and a discharge 40 chamber, a measuring device in said feed controlling chamber, a piston in said discharge chamber, a sliding framework ex-

teriorly of said casing associated with said piston, a power shaft to actuate said measuring device and said framework, a pair of pins on said framework, retractile springs associated with said pins, percussion plates carried by said framework, and recoil springs coöperating 45 with said percussion plates. 50

7. An automatic stoker comprising a centrally located casing, said casing having a feed controlling chamber and a discharge chamber, a measuring device in said feed controlling chamber, a piston in said discharge chamber, a sliding framework exteriorly of said casing associated with said piston, a power shaft to actuate said measuring device and said framework, a cam interposed between said power shaft and said framework, a pair of pins on said framework, retractile springs associated with said pins, percussion plates carried by said framework, and recoil springs coöperating 55 with said percussion plates. 65

8. An automatic stoker comprising a centrally located casing, said casing having a feed controlling chamber and a discharge chamber, a measuring device in said feed controlling chamber, a piston in said discharge chamber, a sliding framework exteriorly of said casing and mounted thereon, adapted to reciprocate, a stem transversely of said framework carried with said piston, a power shaft to actuate said measuring device and said framework, a retractile spring associated with said stem, and a recoil spring coöperating with said framework. 70 75

In witness whereof, I hereunto subscribe 80 my name this 29th day of January, A. D. 1916.

GEORGE A. KOHOUT.
